UNITED STATES PATENT OFFICE.

CHARLES MESSICK, OF BRENTWOOD, NEW YORK.

METHOD OF COMBUSTION CONTROL AND APPARATUS THEREFOR.

Application filed July 13, 1922. Serial No. 574,759.

To all whom it may concern:

Be it known that I, CHARLES MESSICK, a citizen of the United States, residing at Brentwood, in the county of Suffolk and State of New York, have invented certain new and useful Improvements in Methods of Combustion Control and Apparatus Therefor, of which the following is a description.

An object of my invention is to provide an improved method to control combustion, particularly of coal, or other solid fuel, so that the rate of combustion may be effectually and quickly varied and, if required, maintained automatically at a very low rate.

Another object is to provide an improved apparatus in which my method may be practiced, which will be reliable and substantially as low in first cost and maintenance as the apparatus which it is designed to replace.

Another object of my invention is to combine a temperature controlled means with a valve in a passage connecting the ash pit and diving flue of a furnace and also, if desired, to control the draft intake by said means, whereby increased efficiency of control of the fire may be effected.

Other objects may appear from the following detail description of a specific application of my method and a specific form of apparatus in which the method may be practiced.

The preferred form of my improved method consists of connecting the chimney suction permanently to the top of the fire through the combustion chamber and fire passages which terminate at or below the level of the grate bars. The chimney suction being opened into the ash-pit at the level of the grate bars when it is desired to decelerate combustion and if necessary completely smother it without breaking the vacuum created by the suction of the chimney, thus at all times avoiding gas leakage.

In regulating and controlling the fire by this method any leakage of the furnace is inward and in the preferred form of the apparatus, I arrange the combustion chamber, fire passages, and damper so that they will be all self-cleaning, the collected soot and dust automatically falling into the ash-pit. The necessity for so-called clean-out openings is thus eliminated.

The apparatus of my preferred construction is designed to be built so that even though it be operated for years no accumulation of soot or dust will occur, either in the

furnace proper or in the standpipe of the flue connecting the furnace to the chimney, and this is of very real importance, for the reason that neglect to remove dust and soot from the horizontal furnace flues through the clean-outs in the conventional type of apparatus frequently impairs their efficiency to a very considerable extent.

The drawings show a small hot water heating furnace for a private house and when in operation at full load in cold weather this heater may be expected to give results equivalent to the best furnaces of conventional type and similar size and perhaps a slightly higher efficiency owing to the improved arrangement of the fire passages.

When the conventional furnace is operated at very light load in mild weather, all sorts of expedients are resorted to to keep the fire down; such for instance, as opening the feed door, letting ashes accumulate on top of the grates, or even putting them on top of the fire, so as to decrease the draft. Under such conditions of light load my improved method of control and superior design of apparatus exhibits much higher fuel efficiency and may also be operated with less fuel than the conventional type of heater, as well as being operated with much less personal attention. This is because the fire can be kept as low as need be without the opening of the feed door, clogging the draft with ashes, etc.

With my improved method of combustion control, and my improved apparatus, the fire may be thoroughly shaken, heaped up with fresh coal and left for several days under thermostatic control and without personal attention; the combustion only proceeding at a rate sufficient to supply the required heat and no more. With the conventional method and apparatus this cannot be done as well for the conventional dampers are less effective.

With my method and apparatus I am able to approximate the very excellent economy of an automatic gas water heater, for I can quickly reduce an intensely hot fire to a very dull one and yet waste no fuel, whereas with a conventional coal burning furnace this is impracticable.

Draft is essential to the burning of coal and other solid fuel. Natural draft is far more common than forced draft. Natural draft operates on the thermo-siphon principle and one of the reasons for the superior

efficiency of my method and apparatus is that I never have to open the feed door to check my fire. Opening the feed door lets in cold air which cools the chimney, and cooling the chimney reduces the available draft when a sudden demand for more heat occurs. My chimney is always hot and I can therefore always accelerate combustion rapidly.

My apparatus may be likened to an inverted U-tube, having equal legs which both open into an ash-pit when the fire is damped, the ash-pit being at all times evacuated by the chimney draft and thus the escape of gas into the room prevented. There is no circulation of air up through the fire when my damper is open, even though there be leaks in the ash-pit, etc., for both legs of the U-tube open into the chimney draft evacuated ash-pit at the same level. However, it should be understood that there must be permitted at all times a slight venting up the chimney of the waste gases to keep the fire alive even though burning very slowly.

Continuing the analogy, when the fire is to burn briskly, the ash-pit below the leg of the inverted U-tube which includes the fire is opened to atmosphere by a conventional draft flap and the other leg is closed to the ash-pit by the closing of the damper, thus there is a circulation of fresh air up through the fire, out through the chimney, and rapid combustion occurs.

While the damper and the draft flap may be operated independently and by hand, better results are obtained when they are coupled together and controlled by a conventional thermostatic regulator. The heat is thus supplied only as required and a very high over-all efficiency obtained.

When the several factors are thus combined, they cooperate to provide a greatly improved flexibility and economy of solid fuel combustion as compared to the conventional method and apparatus, particularly when only a small amount of heat is required, or when a brisk fire should be quickly reduced to a very low fire.

While it is preferable to include all the steps of my method and the features of the apparatus of my preferred construction, nevertheless, any of the individual and novel steps of my method, or features of my apparatus, singly or in combination, may be beneficially applied to conventional practice; the scope of my invention being measured by my appended claims.

Referring to the accompanying drawings: Fig. 1 is a front elevation of a vertical sectional hot water boiler provided with my combustion control devices, and in which my method may be practiced;

Fig. 2 is a side elevation of the boiler of Fig. 1, partly broken away and in section;

Fig. 3 is a cross-section of the boiler taken on the line 3—3 of Fig. 2;

Fig. 4 is a view of the starting damper of the boiler taken on the line 4—4 of Fig. 2;

Figs. 5, 6, 7 and 8, are diagrammatic illustrations of my system as applied to four different conventional types of boilers.

Referring to Figs. 1 to 4: Numeral 1 indicates a base which forms an ash-pit 3, and supports the grates 5 and the boiler 7. Within the boiler 7 are formed the fire-pot 9 containing a fire-body 10, and the combustion chamber 11 from which the products of combustion normally travel through the ports 13—13 into the diving flue 15. This diving flue 15 is water jacketed by sections of the boiler as indicated, to increase the heating surface and after descending through it the products of combustion pass up the flue pipe 16, which is designed to be connected to the chimney.

The arrows of Figs. 2 and 3 indicate the flow of the products of combustion after the fire is lighted and in normal operation.

When the boiler 7 is cold and fire is to be kindled, the starting damper 17 is opened by being thrust to the right from the position shown in Fig. 4. After the fire is burning brightly and the chimney heated so as to draw well, this damper 17 is returned to the indicated position, where it is permitted to remain as long as the fire is alight. Should this damper 17 be left open continuously, the control of the fire would be less perfect; particularly when little heat was required, as the draft cannot be completely neutralized by the controller 35 (to be described later) when damper 17 is open.

Theoretically, the rapidity of combustion can be perfectly controlled in the conventional type of furnace or boiler. Owing to the unfinished castings, which are used to eliminate the cost of machine work and to the uneven thermal expansion, or contraction, between the various parts of the boiler, however, such control cannot be effected in practice.

My method of control is designed to be practiced in apparatus made of unfinished castings, to tolerate leakage, and yet give perfect control.

Referring to Fig. 2, a thermostat 19, designed to be operated by change of temperature of the water and positioned at the top of the boiler 7 is provided with an arm 21, having an adjustable counter-weight 23 at one end and supporting the center of a balancing beam 25 at the other end. From the ends of beam 25, chains 27 and 29 are suspended, the lower end of chain 27 being attached to a conventional draft flap 31, having a weight 33 to hold it normally closed against the weight of the controller 35. The controller 35, which is merely a hinged flap, is held up and closed in the indicated manner by the chain 29, acting through the lever 37, which is attached to the

externally projecting pivotal portion 39 of the controller 35.

The controller 35 is designed to move in the direction of the arrow 41 of Fig. 2.

- 5 When the controller 35 is opened in this direction it permits free circulation between the air in the ash-pit 3 and the products of combustion ascending into the flue 16, and destroys the draft through the fire 10. 10 When controller 35 is open, it also permits all the soot which may have collected in the diving flue 15 and the flue 16 to fall by gravity into the ash-pit 3. The level of the bottom of the diving flue 15, where it communicates with flue pipe 16, with relation to the level of the grates 5, affects the quickness with which the controller 35, when opened, checks the fire. The lower the opening between diving flue 15 and flue pipe 16, the more quickly controller 35 checks the fire, and conversely, the higher the passage from diving flue 15 to flue pipe 16 the more slowly the controller 35 checks the fire. Thus when starting damper 17 is open 25 controller 35 can only check the fire slowly.

Assuming the fire to be burning normally and the parts to be in the indicated position and the water to become too cool, the thermostat 19 will lower the counter-weight 23 and raise the center of the beam 25. Referring to Fig. 2, where all parts of the apparatus are shown in neutral position, it will be seen that the controller 35 is closed, so that the chain 29 prevents the right-hand 35 end of the beam 25 from rising and compels chain 27 to lift draft flap 31, which permits air to enter beneath the grates 5 and accelerate the fire.

Now assuming the water to have become 40 too hot, the thermostat 19 lowers beam 25, which first permits the draft flap 31 to close by gravity, and the parts to return to the indicated position, after which, as beam 25 continues to descend, the weight of controller 35 causes it to open and destroy the draft through the fire 10, thus quickly decelerating combustion.

Fig. 5 shows a boiler of the same general type as that described in Figs. 1 to 4, except 50 that the fire passages are longer. The arrow 50 shows the path of the products of combustion.

Fig. 6 shows a conventional type of boiler 55 in which the diving flue 60 is external to the boiler proper. The controller is indicated at 61, a clean-out opening at 62, and the arrow 63 shows the normal path of the products of combustion.

Fig. 7 shows a small hot water boiler 60 equipped with a conical form of controller valve 70, and the normal path of the products of combustion is indicated by the arrow 71.

Fig. 8 shows a conventional horizontal fire 65 tube boiler. The arrow 80 indicates the

normal travel of the products of combustion. The controller is indicated at 81 and the kindling damper at 82.

I do not limit myself to the construction shown and my invention is measured by the 70 appended claims.

I claim:

1. A hot water boiler having an ash pit, provided with a thermostat operated by the temperature of the water, and means operated by the thermostat to open the ash pit to chimney draft for slow combustion, close the ash pit to chimney draft for normal combustion, and close the ash pit to chimney draft and open it to atmosphere for accelerated combustion. 75

2. A furnace including an ash pit, a fire pot, a combustion chamber provided with a diving flue, the fire pot and combustion chamber being enclosed by a space designed 85 to contain a circulating fluid to carry the heat away from said fire pot and combustion chamber for use at a distance, a normally closed chimney connection to the ash pit and thermostatic means, governed by the 90 temperature of the circulating fluid to open the connection when combustion is to be decelerated.

3. A furnace including a fire pot and a combustion chamber, an enclosed space surrounding the fire pot and combustion chamber and designed to contain a circulating fluid to carry the heat from the fire pot and combustion chamber away from the furnace for use at a distance, a diving flue from the 95 combustion chamber to a chimney connection and an ash pit also provided with a normally closed chimney connection designed to be opened to decelerate combustion when the circulating fluid becomes too warm and thermostatic means to open the normally closed chimney connection when combustion 100 is to be decelerated. 105

4. A furnace in which the combustion of solid fuel may be effected, provided with a diving flue designed to be connected to a chimney and also provided with an ash pit, a passage connecting the diving flue and the ash pit provided with a valve and a thermostatic device connected to the valve, for the 110 purpose of opening or closing the valve to control the combustion in the furnace. 115

5. A furnace in which the combustion of solid fuel may be effected, provided with a diving flue designed to be connected to a chimney and also provided with an ash pit having a draft opening and means to open or close same, a passage connecting the diving flue and the ash pit provided with a valve and a thermostatic device connected to the valve and the means, for the purpose of opening or closing the valve and the means to control the combustion in the furnace. 120 125
